UNITED STATES PATENT OFFICE.

MARCUS ASH MYERS, OF GLOVERSVILLE, NEW YORK, ASSIGNOR TO MYERS' WOOLLY ANIMALS, INC., A CORPORATION OF NEW YORK.

DESIGN FOR A CARRYING BAG.

Application filed June 25, 1927. Serial No. 22,555. Term of patent 7 years.

To all whom it may concern:

Be it known that I, MARCUS ASH MYERS, a citizen of the United States of America, residing in Gloversville, county of Fulton, and State of New York, have invented a new, original, and ornamental Design for a Carrying Bag, of which the following is a specification, reference being had to the accompanying drawings, forming a part thereof.

Fig. 1 is a perspective view of a carrying bag illustrating my new design.

Fig. 2 is a plan view thereof.

I claim:

The ornamental design for a carrying bag, substantially as shown.

This specification signed this 17th day of June, 1927.

MARCUS ASH MYERS.
